[57] CLAIM

The ornamental design for an underwater console attaching slate board, as shown and described.

DESCRIPTION

FIG. 1 is a rear elevation of an underwater console attaching slate board, showing my new design;

FIG. 2 is a front elevation thereof;

FIG. 3 is a side elevation thereof; and

FIG. 4 is an elevation of the side opposite FIG. 3.

FIG. 5 is an end elevational view, and

FIG. 6 is an end elevational view taken from the end opposite to that of FIG. 1 and with the slate being turned over.

The broken lines are shown for illustrative purposes only.
